PILOT BURNER AND FLAME RETAINING MEANS

Filed Feb. 16, 1949

UNITED STATES PATENT OFFICE

2,591,458

PILOT BURNER AND FLAME RETAINING MEANS

Le Roy A. McGuire, Leonardo, N. J., assignor to
Peabody Engineering Corporation, New York,
N. Y., a corporation of New York

Application February 16, 1949, Serial No. 76,770

2 Claims. (Cl. 158—115)

1

This invention relates to gas burners and more particularly to a burner tip having novel and improved characteristics.

An object is to provide a tip which will ignite and retain its flame even in a strong blast of air.

Another object is to provide a tip for burning gases of different B. t. u. contents.

Another object is to provide a novel and improved tip for burner ignitors which is dependable and stable in operation.

Various other objects and advantages will be apparent as the nature of the invention is more fully disclosed.

Although the novel features which are characteristic of this invention are pointed out more particularly hereinafter, the nature of the invention will be better understood by referring to the following description, taken in connection with the accompanying drawings, in which a specific embodiment thereof has been set forth for purposes of illustration.

In the drawings:

Fig. 1 is a longitudinal section through a typical burner showing the igniter in one position for ignition;

Fig. 1a is a diagrammatic end elevation of the burner of Fig. 1 showing a representative orientation of the igniter tip in the burner air stream;

Fig. 2 is a side elevation of the igniter on a larger scale with parts broken away to show the construction thereof;

Fig. 3 is a fragmentary elevational view of the igniter tip shown in Fig. 2; and

Fig. 4 is a transverse section of the igniter tip taken on the line 4—4 of Fig. 3.

Referring to the drawings more in detail, the invention is shown as applied to a conventional fuel burner including a burner tube 10 through which the combustion air passes in the form of a rotating mass, an air register 11 having air doors 12 through which this air is admitted to the burner tube, a front plate 13 at the front of the wind box, a furnace wall 14 having a throat 15 registering with the burner tube, a fuel admission ring 16 located around the burner tube 10 adjacent the throat 15 and a fuel atomizer 17 which supplies other fuel for combustion. The burner may also be adapted to burn powdered fuel suspended in carrier air as is well known in the art.

The igniter, according to the present invention, comprises a body 20 (Fig. 2) having an axial passage 21 and provided at one end with flanges 22 which are secured by bolts 23 to a casting 27 carrying the control elements to be described. At its other end the igniter body 20 carries a pair

2

of ignition electrodes 25, one of which may be grounded to the body 20 by a cap 26, and the other of which may be insulated by and supported in a spark plug 27 which is connected by a cable 28 to the high tension side of a transformer 29 which is mounted in a housing 41 attached to the casting 24 or formed integral therewith. A sight glass 42 is shown as mounted in the body 20 over the electrodes 25. The electrodes, sight glass, cables, casting, transformer and associated parts are sealed against the pressure in the wind box.

The body 20 is also provided with a coupling flange 30 in which a tube 31 of any desired length is secured. The tube 31 is slidable in an outer tube 43 which extends through the front plate 13, as indicated in Fig. 1, and projects at its inner end through the burner tube 10. The tube 31 extends through a stuffing box 44 which is secured to the front plate 13 by bolts 45 and supports the outer tube 43. The tube 31 carries a tip 32 which is positioned within the burner tube 10 in the path of the air stream therein and adjacent the fuel streams to be ignited.

The tip 32 is shown in the form of a flared U-shaped housing 33 (Fig. 4) which is coaxial with the tube 31 and is closed at the two ends by plates 34. The flared side of the U-shaped member 33 is closed by a front plate 35 which is inclined to the axis of the U-shaped member 33 and of the igniter tube 31 and is provided with a central opening 36 through which the gas for combustion passes. The plate 35 is spaced from the extremities of the U-shaped member 33 and of the end plates 34 to form upstanding peripheral flanges 40 which extend entirely around the periphery of the plate 35 to shield the same from the blast of secondary air in the burner tube and to form eddy currents which serve to hold the igniter flame against the plate 35. The plate 35 is inclined in the direction of air flow towards the burner throat 15 so that the flame passing from the aperture 36 therein is directed towards the ignition zone of the burner. A lateral flange 46 extends outwardly from the side of the member 33 exposed to the rotating air stream and an end flange 47 having an upstanding lip 48 is mounted on the end plate 34 towards the air register 11. The U-shaped member 33 is preferably placed at such an angle with respect to the direction of air flow through the burner tube 10 that the air passes over the curved surface of the U-shaped member 33 so as to flow in a general direction from its closed end toward the open end thereof whereby the member 33 serves to deflect the air blast away from the igniter flame projecting from the ap-

erture 36 and the flanges 40, 46 and 47 producing eddy currents to hold the flame to the plate 35 and preventing its being blown out by the force of the air blast.

The housing 87 carries an air valve housing 50 and a gas valve housing 51.

The housing 87 carries a cover on which an index plate 111 is mounted.

A lead 78 connects the primary of the transformer 29 to a switch in the housing 87 and a low tension lead 79 extends from the switch 100 to a suitable source of current such as the usual 110 volt supply.

A valve operating handle 120 carries a pointer 117 registering with an index carried by the index plate 111.

It is to be understood that the tip may be located axially of the burner or may pass through the air register if desired. A specific location has been shown for purposes of illustration only.

In the construction above described, a stable flame is produced at the tip 32 which is not blown out by the blast of air through the burner tube 10. While the angular position of the tip in the burner tube 10 may be varied somewhat, the best results are obtained when the closed end of the member 33 is pointed in the direction of air flow so that the air passes around the outside of the member 33. The flanges 40, 46 and 47 provide turbulence which retains the flame on the surface of the plate 35. Due to the difference in depth of the flange 40 around the different portions of the periphery of the plate 35, a proper degree of turbulence is maintained over at least one portion of the plate 35 to support combustion under the different conditions of use. In certain instances it may be desirable to mount the plate 35 in a plane parallel to the axis of the tube 31 or to form the flanges 40 of the same depth around the entire plate. The construction shown, however, has been found to operate satisfactorily over a wide range of burner conditions and to maintain a stable ignition flame even when the combustion air within the burner tube 10 is turned on suddenly.

The invention is particularly adapted for use with large size industrial burners although its application is not to be restricted thereto. The igniter is not to be restricted to use with a

burner, but may be used in various instances where the initial ignition at the electrodes takes place under conditions to cause incomplete combustion and the air to complete the combustion is present at the tip. Hence the device is not dependent upon the heat content of the fuel supplied as sufficient air for complete combustion is supplied at the remote tip.

Various changes and adaptations may be made in the various details of construction without departing from the scope of the invention.

What is claimed is:

1. A gas igniter for use in a stream of combustion air, comprising an igniter tube for carrying a combustible gas and having a tip at its exit end to be positioned in the path of said combustion air, said tip comprising a U-shaped housing having flared side wall having end walls and a front plate spaced inwardly from the outer ends of said side walls and forming therewith a chamber having a U-shaped transverse section, one of said end walls having a gas supply opening registering with said igniter tube with said side wall extending beyond the exit end of said tube parallel to the axis thereof, said front plate having a gas discharge opening therein through which the gas flows for combustion, said front plate being inclined in a plane intersecting the axis of said tube beyond said tip whereby the gas stream from said plate opening is directed laterally relative to the igniter tube, said side and end walls extending laterally above said front plate and thereby forming a flange therearound to shield the igniter flame from the surrounding air stream.

2. In a gas igniter, as set forth in claim 1, a flange on and parallel to at least one edge of said side wall extending outwardly and substantially normal to said wall to shield the front plate and form eddy currents for stabilizing the flame.
